UNITED STATES PATENT OFFICE.

GEORGE N. RUSSEL, OF LAWRENCE, KANSAS, AND ORSON W. RUSSEL, OF KANSAS CITY, MISSOURI.

DESIGN FOR A TRAFFIC-SIGNAL.

59,785.

Specification for Design.

Patented Nov. 22, 1921.

Application filed July 5, 1921. Serial No. 482,599. Term of patent 7 years.

To all whom it may concern:

Be it known that we, GEORGE N. RUSSEL, a citizen of the United States, residing at Lawrence, in the county of Douglas and State of Kansas, and ORSON W. RUSSEL, a citizen of the United States, residing at Kansas City, in the county of Jackson and State of Missouri, have invented a new, original, and ornamental Design for Traffic-Signals, of which the following is a specification, reference being had to the accompanying drawing, forming part thereof, in which—

A perspective view of our new design is shown.

We claim:—

The ornamental design for a traffic signal, as shown.

GEORGE N. RUSSEL.
ORSON W. RUSSEL.
